UNITED STATES PATENT OFFICE

140,067

DESIGN FOR A BROOCH OR SIMILAR ARTICLE

Simon Fischer, Brooklyn, N. Y.

Application November 16, 1944, Serial No. 116,356

Term of patent 7 years

(Cl. D45—19)

To all whom it may concern:

Be it known that Simon Fischer, a citizen of the United States and resident of the Borough of Brooklyn, in the county of Kings and State of New York, has invented a new, original, and ornamental Design for a Brooch or Similar Article, of which the following is a specification, reference being had to the accompanying drawing, forming part thereof, in which

Fig. 1 is a front elevational view of a brooch embodying my new design;

Fig. 2 is a top edge view thereof; and
Fig. 3 is a side view thereof.

The dominant feature of the invention resides in the portions shown in full lines.

I claim:

The ornamental design for a brooch or similar article, substantially as shown and described.

SIMON FISCHER.
